Robert A. Sloman
ATTORNEY:

UNITED STATES PATENT OFFICE

2,567,013

MULTIPLE GAS BURNER FOR FURNACES

Charles E. Feinberg, Detroit, Mich.

Application March 28, 1946, Serial No. 657,847

1 Claim. (Cl. 158—7)

1

This invention relates to a gas burner, and more particularly to a burner construction adapted for house or building heating.

Heretofore in construction of this type, there has been the problem of most efficiently utilizing the combustible mixture of gas and air.

It is therefore the object of the present invention to provide a novel gas burner construction designed to effect the greatest utilization of the heat of combustion.

It is the further object of this invention to provide a novel gas burner tip having a plurality of longitudinally arranged slotted flame sources whereby the flames produced have an upward wall sweeping or washing effect to produce the maximum transfer of heat to the furnace wall.

It is the still further object of this invention to provide a hollow gas manifold upon which are positioned a plurality of radially arranged burner tips, each of which has a plurality of spaced longitudinally slotted arcuate flame sources, whereby a plurality of substantially continuous concentric rings of flame are produced to upwardly impinge and sweep over the furnace walls.

These and other objects will be seen from the following specification and claim in conjunction with the appended drawing in which:

Figure 1 is a prospective view of the complete burner.

Figure 2 is an elevational section of the burner positioned within a furnace which is fragmentarily shown; and

Figure 3 is an enlarged elevational section of a single burner tip and its mounting upon the gas manifold.

It will be understood that the above drawing illustrates merely one preferable embodiment of the invention, and that other embodiments are contemplated within the scope of the claim hereinafter set out.

Referring to the drawing, a hollow furnace shell 11 is fragmentarily shown, within which is positioned the hollow cylindrical base 12 in centrally spaced relation.

The annular furnace fire walls 13 and 14 mounted on base 12 have a vertical axis and form a fire chamber providing means of transferring the heat of combustion to the air, for instance, which passes through the space 15 for subsequent direction to various parts of the building to be heated in the conventional manner.

The gas burner (Figure 1) is centrally positioned within fire walls 13 and 14, with its gas manifold 16 adjustably mounted upon the three

2

legs 17. The latter slidably extend through openings in flanges 18 through which are threaded transverse locking studs 19. Thus manifold 16 may be adjustably arranged at the proper level for the particular fire chamber employed.

Hollow circular gas manifold 16 of substantially rectangular cross section has a plurality of radially spaced threaded openings within which 10 are positioned threaded nipples 20, preferably made of brass. A hexagonally shaped nut portion 21 is provided to facilitate the positioning of said nipples securely within manifold 16. It will be understood that manifold 16 may be of some 15 other shape such as rectangular, if desired.

The lower open ends 22 of hollow burner tip 23 are slidably positioned over the upright portions 23' of said nipples. The enlarged gas intake opening 24 of nipple 20 terminates in 20 the constricted discharge opening 25 for conducting gas at increased velocity into mixing chamber 26.

As illustrated in Figure 3, air intake openings 27 are provided in burner tip 23 so that the stream 25 of gas into chamber 26 draws with it a supply of atmospheric air to produce a highly combustible mixture within chamber 26.

Burner tip 23 has a plurality of stepped hollow transversely curved projecting portions 28, 30 and 30 with horizontally slotted outlets 31. Member 28 extends outwardly the farthest, with members 29 and 30 being stepped and spaced inwardly.

As shown in Figure 1 it will be seen that burner tips 23 are arranged so that the slotted curved outlets 31 respectively of each of the burner portions 28, 29 and 30 form substantially continuous concentric circles.

Thus it is clear that, when ignited, a plurality 40 of substantially concentric circles of flame are produced which sweep upwardly against the inner walls of fire chamber 13—14. Members 28 produce a circle of flame of maximum diameter, while members 30 produce a concentric elevated 45 circle of flame of least diameter. At the same time an intermediate concentric circle of flame is produced from the mouths 31 of members 29.

It has been found that longitudinally curved slotted outlets 31 provide a particularly effective 50 flame characteristic for yielding the maximum heat to the maximum surface area of fire walls 13—14.

Due to the upward draft through the furnace it has been found that the concentric circles of 55 flame have an upward rolling and wall-sweeping

or wall-washing effect to produce the maximum heat transfer.

The circular spacer manifold plate 32 has an annular flange 33 which depends downwardly and projects between the spaced vertical projecting portions 34 of burner tips 23 to effectively support said tips in the circular arrangement shown in Figure 1.

A plurality of openings 35 are formed within the top of plate 32 to permit the upward passage of air through the furnace. Hollow gas manifold 16 has a threaded fitting 36 to which may be joined a suitable gas source which is distributed to the plurality of burner tips 23 through the interconnecting nipples 20.

Having described my invention, reference should now be had to the claims which follow for determining the scope thereof.

I claim:

The combination, annular walls having a vertical axis and forming a fire chamber, a circular gas manifold therein coaxial with said fire chamber and joined to a gas source, a plurality of spaced vertically extending gas burners circumferentially distributed and joined to said manifold, and a plurality of vertically spaced sector shaped coaxial burner tips on each burner, with the arcuate portion of each tip having a horizontal elongated constricted and outwardly

directed outlet slot, the corresponding burner tips of said burners at corresponding levels being arranged in substantially coaxial circles of vertically decreasing radii, and arranged for impingement upon said fire chamber.

CHARLES E. FEINBERG.
